CENTRIFUGAL PUMP

Earle E. Schroeder, Norwood, Ohio, and Leonard H. Smeltzer, Jr., South Fort Mitchell, Ky., assignors to Allis-Chalmers Manufacturing Company, Milwaukee, Wis., a corporation of Delaware

Filed Jan. 8, 1963, Ser. No. 73,087

Term of patent 14 years

(Cl. D65—1)

Fig. 2

FIG. 1 is an isometric view of a centrifugal pump, showing our new design.

FIG. 2 is an orthographic end view of FIG. 1 looking from the right end.

FIG. 3 is an enlarged partial view of FIG. 1.

The side opposite that shown in FIG. 1 is substantially a mirror image thereof except as indicated in FIG. 2.

We claim:

The ornamental design for a centrifugal pump, as shown and described.
